UNITED STATES PATENT OFFICE.

ALEXANDER B. RONEY, OF CHICAGO, ILLINOIS.

AIR TRACTOR-ENGINE.

1,330,346.

Specification of Letters Patent. Patented Feb. 10, 1920.

Application filed February 17, 1919. Serial No. 277,602.

To all whom it may concern:

Be it known that I, ALEXANDER B. RONEY, a citizen of the United States, residing at Chicago, county of Cook, and State of Illinois, have invented a new and useful Air Tractor-Engine, of which the following is a specification.

The object relates to the propulsion of aircraft regardless of the direction of the wind.

10 Figure 1 is a partial longitudinal section of Fig. 2 on the line (D—D).

Fig. 2 is a cross-end view of Fig. 1 on the line (C—C).

15 Fig. 3 represents a face view of the perforated plate.

The drawings disclose a circular series of reciprocating pumps (1), a rotary propeller (2), and an intake plate (3), partially enclosed in a tubular casing (4), having one 20 end (5) open with the other end closed, but casing (4) has inlet and outlet portways controlled by check valves (7 and 8) that are, in this instance, made of sheet rubber.

25 The purpose of the pumps is to maintain a steady displacement of the air from said casing out through the portways and past the check valves that prevent its return. Then the atmospheric pressure responsive to the low pressure in the casing flows in, only

30 to be kept going on out through the portways by the pumps, thus maintaining a steady air blast against the blades of the propeller, which is adapted to revolve past the perforations of plate (3) that concen-

35 trate the air flow against the propeller causing it to react against the casing for the forward propulsion. The plate (3) is not an essential feature.

30 The piston parts (15) of the pumps are adapted to be reciprocated by the drive shaft (9) through the medium of the drum

(10), which is fastened to the shaft and is provided with an oblique slotway (11) that is cut around the surface of its periphery

45 and into which the off-set ends (12) of the piston rods (13) are meshed between guides (14) for engagement with the sides of said slotway, and the propeller (2) also is driven by the same drive shaft (9), which, when

50 operated by a motor, also turns the drum (10) to move the pistons back and forth and thereby displacing the air on the pressure

side of the pistons out through valves (8), and at the same time drawing in air from the casing (4) through valves (7).

55

The pumps (1) which are contained in the casing (4) are divided on the line (c—c) into separate half parts to facilitate machining of the cylinders and assembling of the pistons (15) thereto. When these half 60 parts are jointed together, the adjacent air spaces (16) between the pumps (1—1—1—1) are continuous throughout the length of casing (4) from the closed to the open end, and serve as draftways to supply the pistons 65 moving from the closed end with air from the open end, which the return stroke discharges out through the check valves situated at the closed end, but draftways (16) are not used for the reverse stroke, which starts 70 at the open end and discharges through the check valves situated at the open or propeller end of casing (4). The draftways (16) and the extra set of check valves situated at the closed end of casing (4) on the 75 one hand and the set of check valves situated at the open end on the other makes the pumps double acting for each revolution of the drive shaft.

Now here is a case of pump air displacement matched against rotary propeller air displacement in the same casing, both driven by the same drive shaft and wherein the pump displacement, being the strongest of the two, prevails and determines that the direction of the air blast shall be on out through the portways.

80 By these means all the power borrowed from the drive shaft by the propeller to oppose the pumps is recovered through its reaction against the casing and thereby transformed into propelling thrust for the forward propulsion.

90 I claim—

In an air tractor engine, in combination, 95 a casing having one closed and one open end, a propeller in said open end, an air pump in said casing adapted to displace the air from the rear of said propeller and a means for driving said propeller and said pumps.

ALEXANDER B. RONEY.
